TOASTER-OVEN

Bruce A. Claxton, Springfield, Pa., assignor to
SCM Corporation, New York, N.Y.

Filed Apr. 24, 1974, Ser. No. 463,699

Term of patent 14 years

Int. Cl. D7—02

U.S. Cl. D7—93

FIG. 4

FIG. 6

FIG. 5

FIG. 7

FIG. 1 is a front perspective view of a toaster-oven showing my new design;

FIG. 2 is a top plan view thereof;

FIG. 3 is a front elevational view thereof;

FIG. 4 is a rear elevational view thereof;

FIG. 5 is a right side elevational view thereof;

FIG. 6 is a left side elevational view thereof; and

FIG. 7 is a bottom plan view thereof.

I claim:

The ornamental design for a toaster-oven, as shown.
